UNITED STATES PATENT OFFICE.

ELMER LEWIS LEE AND EUGENE T. DE WITT, OF DENVER, COLORADO.

CAR-DOOR.

1,142,588.

Specification of Letters Patent.

Patented June 8, 1915.

Application filed July 2, 1914. Serial No. 848,616.

To all whom it may concern:

Be it known that we, ELMER LEWIS LEE and EUGENE T. DE WITT, citizens of the United States, residing in the city and county of Denver and State of Colorado, have invented certain new and useful Improvements in Car-Doors, of which the following is a specification.

This invention relates to an improvement in car doors, and has to do more particularly with the type of car door set forth in our joint application filed January 6, 1914, Serial No. 810,551, the present invention involving some of the features of that invention, although simplified in form, and also certain novel features of construction and combinations of parts which will be herein-after more fully described and pointed out in the claim.

In the accompanying drawings, Figure 1 is a side elevation of a portion of a car showing our improved door closed; Fig. 2 is an enlarged detail in section through a portion of the car and the upper right-hand corner of the door; Fig. 3 is a side view and plan of the wedge located on the door; Fig. 4 is a side view in plan of the wedge on the car body adjacent to the rear edge of the door; Fig. 5 is an enlarged transverse section through the lower portion of the car showing the lower edge of the door; Fig. 6 is a side elevation, plan and end elevation of the wedge secured to the top of the door for forcing the latter down when closed; Fig. 7 is a plan in side elevation of the top rail, parts being broken out at the center; Fig. 8 is an enlarged side elevation of one of the lower brackets; Fig. 9 is an enlarged edge view of the forward edge of the door and showing the car body in section with the latch applied thereto; Fig. 10 is an enlarged side view of the door-opener; Fig. 11 is a plan view of the hasp; Fig. 12 is a plan and side elevation of the catch at the rear edge of the door; Fig. 13 is a side elevation in plan of the door-stop at the rear end; Fig. 14 shows the catch-strap in two different positions at right-angles; and Fig. 15 is a fragmentary horizontal sectional view through the lower edge of the door, showing the beveled corners at diagonally opposite points.

The numeral 1 indicates the car, portions only of which are shown; and 2, is the door, mounted on rollers 3, 3, at the bottom, which are held in brackets 4, 4, secured to the side

of the car beneath the door, the upper edge of the door being confined by the guard-track 5. These present improvements in the main contemplate means for holding the door tight to the car body at all four corners when closed, and for forcing it outward therefrom as the door is unfastened and opened. To this end the guard-track 5 is provided with the incline 6 at the forward corner, as shown in detail in Fig. 7, against which the upper left-hand corner of the door strikes when closed, whereby it is forced inward securely against the body of the car. At the upper right-hand corner of the door a bracket 8, shown in Fig. 6, is secured. This has an incline 9 thereon, and a roller 10 carried on the bracket 11 secured to the side of the car above the door by traversing this incline forces the door downward as well as inward at the rear edge. At the lower left-hand corner, a guard 12 having an incline 13 similar to incline 6 on the guard-track 5 is secured, the inner end thereof being held by the adjacent bracket 4, and the corner of the car-door by striking the inner face of the incline 13 is forced inwardly. At the right-hand corner, the bracket 14 corresponding to the several brackets 4 is secured, but this bracket 14 is extended upwardly in the form of an arm 15, as shown enlarged in Fig. 5, the free end of which is in the path of a wedge 16 (see Fig. 3) secured on the corner of the door in position to crowd beneath the upper free end of the arm 15 when the door is closed to hold the lower right-hand corner securely against the side of the car.

A wedge 17 (see Fig. 4) is secured to the side of the car immediately adjacent to the right-hand lower corner of the door in position to be engaged by the door the moment it is forced open to throw the lower edge of the door slightly outward away from the car body, so that it will not scrape against the latter in opening and closing.

A stop 18 is located in position to stop the door when open and receive the spring-catch 19 secured to the right-hand lower corner of the door by screws or bolts 20 and straps 21, (see Fig. 14).

The door when closed is locked by means of the hasp 22, one end of which receives the staple 23 where it is held by a pin, padlock or other fastening means 24. This hasp is pivotally secured on the cam starting lever 25, which lever is fulcrumed at 26 on the

car and has a cam 27 in position to engage the edge of the door when the lever is swung outwardly or to the left after having unfastened the hasp 22. This lever is provided 5 to start the door as it is apt to stick, owing to the tight contact created by the wedges between the door and car-body.

From the foregoing it will be seen that we have provided a door which closes practically 10 air and dust-tight against the car, thus preventing vibration and play, and also the loss of any of the contents of the car.

We claim:—

The combination with a car body, of a 15 door having the forward edge beveled on its exterior surface and the rear edge beveled on the interior surface, rollers on which the door travels, brackets for supporting the rollers on the car body, a guard-track and 20 guard having inclines for forcing one edge

of the car door inwardly against the wall of the car body, the opposite edge of the door carrying wedges at each corner, means on the guard-track engaging one of the wedges for forcing the door inwardly, an extension 25 on one of the roller brackets engaging the other wedge for forcing the door inwardly, and a wedge connected to the car body engaged by the beveled surface on the rear edge of the door for causing the door to be 30 forced outwardly when the door is being opened.

In testimony whereof we affix our signatures, in the presence of two witnesses.

ELMER LEWIS LEE.
EUGENE T. DE WITT.
